UNITED STATES PATENT OFFICE.

ROYAL K. JOHNSON, OF CLEVELAND, OHIO, ASSIGNOR TO THE MINERVA ENGINE COMPANY, OF CLEVELAND, OHIO, A CORPORATION OF OHIO.

INTERNAL-COMBUSTION ENGINE.

1,347,276.

Specification of Letters Patent. Patented July 20, 1920.

Application filed April 17, 1918. Serial No. 229,041.

To all whom it may concern:

Be it known that I, ROYAL K. JOHNSON, a citizen of the United States, residing at Cleveland, in the county of Cuyahoga and State of Ohio, have invented a certain new and useful Improvement in Internal-Combustion Engines, of which the following is a full, clear, and exact description.

This invention relates to internal combustion engines, and particularly to an improved speed regulator. In a more specific aspect the invention relates also to an oil pressure regulator which has the combined functions of regulating the oil pressure in the lubricating system and also to regulate or automatically reduce the speed of the engine when the latter becomes excessive.

One of the principal objects of this invention is to provide a regulator which will gradually decrease the speed of the engine without stopping the engine entirely or reducing the speed to an abnormally low point.

Still further objects are to provide a simple, efficient, self-contained regulator, particularly one which performs the dual functions of controlling the engine speed and governing the pressure of the oil in the lubricating system to avoid excessive pressure and overheating.

The invention may be briefly summarized as consisting in certain novel details of construction and combinations and arrangements of parts which will be described in the specification and set forth in the appended claims.

In the drawing Figure 1 is a side view of the intake manifold of an engine, showing the speed controlling throttle valve and my improved regulator with portions of the piping of the lubricating system, and Fig. 2 is a conventional side view of an engine showing the oil pump and other portions of the lubricating system.

In carrying out my invention I use as a medium for actuating the regulator, a fluid in a circulating system wherein the pressure varies with the engine speed, and I utilize a valve preferably in the form of a piston which is moved from normal position by increase of pressure in this circulating system, this valve or piston being operatively connected to the throttle valve so as to shift the same to govern the mixture passing to the engine. This valve is so con-

structed and arranged that as the pressure rises it gradually by-passes more and more of the fluid in the system from the high pressure to the low pressure side or source of supply by uncovering suitably positioned ports or a relatively long spiral port so that as more of the fluid is by-passed the movement of the valve or piston will be gradually reduced, causing a gradual closure of the throttle valve.

In the broad aspects of the invention it is immaterial what character of fluid is circulated in the system, and what circulating system is utilized, whether a special one provided for use solely with this regulator, or one already utilized on the engine, but preferably the circulating system is the oiling or lubricating system of the engine wherein the pressure of the circulating fluid normally varies with the speed of the engine, for with this embodiment by having the valve or piston shunt or by-pass gradually increasing portions of the oil from the pressure side of the pump back to the crank case or oil supply, the pressure will not increase proportionally with the speed and will not become excessive. The last mentioned embodiment of the invention is the one herein shown, and will now be described.

In the drawing, 10 represents a manifold of the engine E (shown conventionally in Fig. 2), which engine may be of any suitable construction and may be used for any other purposes for which an engine of this type is used, such as for trucks or other vehicles. The manifold is supplied by a conduit 10^a which may be considered a part of the manifold. In this conduit there is provided a throttle valve 11 which is designed to automatically control or regulate the speed of the engine, this valve being preferably separate and distinct from the throttle valve which is manually controlled.

At one side of the conduit 10^a I provide a chamber 12 which as here shown is cast integral with the conduit but such integral construction is not necessary, and extending centrally into the chamber 12 is a barrel or small cylinder 13 which in this instance is formed integral with a plate 14 which constitutes the head or cap of the chamber 12. The barrel or cylinder 13 receives a valve, in this case in the form of a piston 15, which in any suitable manner is connected to the

throttle valve 11, but as here shown is provided with a stem 16 which passes through an adjustable plug 17 and is connected to an arm 18 on the shaft or pin which supports the throttle valve 11. Any other suitable form of connection between the stem and valve, such as rack and pinion connection may be utilized.

Between the piston 15 and the plug 17 10 through which the stem 16 passes and which is adjustably fitted into the base of the chamber 12, is a coil spring 18 which yieldingly resists the inward movement of the piston. By adjusting the position of the 15 plug 17, the compression and resisting action of the spring may be adjusted so as to adapt the regulator for different engine speeds.

The head or outer side of the cylinder 14 20 has connected to it a fluid supply pipe 19 which in accordance with the preferred form of my invention previously described is connected at some suitable point to the pressure line or pipe 20 leading from the 25 oil pump P, shown conventionally in Fig. 2. Additionally the base of the chamber 12 has attached to it an oil return pipe 21, which will lead to the sump of the crank case as indicated in Fig. 2, or to the source 30 of oil supply in whatever form it may be.

To avoid confusion and unnecessary illustration I have not shown a complete oiling system as the particular form of system, and the arrangement of the piping, is important only that the oil be circulated through 35 the system by an engine driven pump.

It will be observed that the barrel or cylinder 14 is provided to the left of the normal 40 position of the piston with a series of spirally arranged ports or outlets 22, which will be successively uncovered as the piston is moved inward from normal position, so as to allow more and more of the oil to be 45 by-passed by the pipes 19 and 21, as the speed increases. It will be understood without illustration that instead of having a series of spirally arranged isolated circular ports 22, rectangular ports or ports of any 50 other shape may be employed, and that a single diagonal or spiral slot may be utilized.

The action of this device is as follows: When the speed is normal or below the 55 determined number of revolutions, no oil will be by-passed around the pump or from the pressure side to the source, due to the fact that none of the ports (or no part of a single port if the latter is employed) is uncovered by the piston, but as the speed increases beyond the predetermined number of revolutions, the piston will be moved inward, uncovering first one port, allowing a certain amount of the oil to be by-passed or 60 to pass from pipe 19 to the return pipe 21,

and if the speed still increases the piston will continue to gradually uncover the succeeding ports, allowing more and more of the oil to be by-passed, thus preventing the pressure building up to an excessive 70 point with its consequent overheating. At the same time that this oil pressure is being gradually reduced or prevented from increasing by the increased by-passing of the oil, the throttle valve is gradually closed, 75 but as more and more of the ports are uncovered the movement of the piston will gradually slow down, the final movement or movements being gradual, and preventing the sudden stopping or sudden decreasing of the speed of the engine below that desired. When the piston has reached practically the limit of its inward movement, which in practice just uncovers the last port, the throttle valve is nearly but not entirely closed, that is to say, it is closed to the extent required to bring about a reduction of the engine speed to the predetermined desired maximum speed. 80

In the respects above stated, this invention 85 has a considerable advantage over the common ball governor which ordinarily has the disadvantage that it slows down the engine speed too quickly and too much, if not altogether stopping it. 90

Additionally this structure not only serves both as an oil pressure governor and a speed governor, but the device is very inexpensive and simple in construction, it being a feature of the construction that no packing 10 is required, for the reason that there is no pressure in the chamber 12, and the height of the oil in the chamber never rises to the level of the stem 16. In fact, the use of a piston ring or extremely accurate fitting of 11 the piston in the barrel is not essential, for any oil which may seep past the piston will pass directly from the barrel to the lower part of the chamber, and return by pipe 21 to the source of oil supply. 12

I do not desire to be confined to the exact details shown, or exact combinations specified, but aim in my claims to cover all modifications which do not involve a departure from my invention in whole or in part, as 13 expressed in the appended claims.

Having described my invention, I claim:

1. In combination with an internal combustion engine having a throttle valve and a circulating system for engine lubricant, 14 high and low pressure by-pass pipes adapted to be connected thereto, and a valve responsive to increase of oil pressure due to increase of engine speed for gradually increasing the by-passing of oil as the engine 15 speed increases, thereby preventing excessive rise of pressure in the lubricating system, said valve being connected to the throttle valve.

2. In combination with an internal com- 16

bustion engine having a throttle valve and a circulating system for engine lubricant, an oil pressure release valve for preventing excessive rise of pressure in the oil circulating system, said valve being connected with the throttle valve so as to simultaneously act as a speed regulator.

3. In combination with an internal combustion engine having a speed regulating valve and a circulating system for engine lubricant, means for preventing excessive rise of pressure in the circulating system including a by-pass valve and by-pass pipes adapted to be connected to the high and low pressure sides of the system, and means connecting the second-named valve to the first-named valve.

4. The combination with an internal combustion engine having a throttle valve for regulating the speed thereof and having a circulating system for engine lubricant, and means for regulating the pressure in the oil circulating system comprising by-pass pipes adapted to be connected to high and low sides of the system, and a valve comprising a piston and a chamber receiving the piston and having its inlet and exhaust sides connected to said pipes and having outlet ports adapted to be successively uncovered by said piston as the pressure in the system increases with increase of speed, said piston being connected to said throttle valve.

5. The combination with an internal combustion engine having a throttle valve and a circulating system for engine lubricant,

means for preventing excessive rise of pressure in the circulating system as the engine speed increases and for simultaneously decreasing the engine speed, said means comprising a chamber, a cylinder or barrel in said chamber, and provided with a plurality of spirally arranged ports, a piston in the barrel or cylinder connected to the throttle valve, and by-pass pipes adapted to be connected to the high and low pressure sides of the system, one of said pipes being connected to the cylinder or barrel and the other being connected to the chamber.

6. The combination with an internal combustion engine having a throttle valve and circulating system for engine lubricant, means for preventing excessive rise of pressure in the circulating system as the engine speed increases and for simultaneously decreasing the engine speed, said means comprising a chamber, a cylinder or barrel in said chamber, and provided with a plurality of spirally arranged ports, a piston in the barrel or cylinder connected to the throttle valve, and by-pass pipes adapted to be connected to the high and low pressure sides of the system, one of said pipes being connected to the cylinder or barrel and the other being connected to the chamber, and adjustable means for yieldingly resisting the movement of the piston.

In testimony whereof, I hereunto affix my signature.

ROYAL K. JOHNSON.
